SLEEVE-VALVE ENGINE

Application filed August 12, 1926. Serial No. 128,784.

This invention relates to internal combustion engines of the sleeve valve type and the primary object is the provision of an engine of this character having a pair of reciprocating sleeves mounted one within the other at the top of the cylinder, these sleeves being operated back and forth in such a way as to cause the proper intake and exhaust of fuel and burnt gases.

10 A further object of the invention is the provision of valve ports, one on each side of the top of the cylinder, each of which communicate with a valve opening in a main stationary chamber or sleeve support above 15 the cylinder.

A further object is the provision of a set 20 of cams which may positively operate the two valve sleeves back and forth in both directions. These cams are so designed that the sleeves are both stationary during the pressure periods of the engine, that is, during the 25 compression and during the explosion periods.

A further object is the provision of a spark 30 plug in each of the ports which are provided between the top of the cylinder and the valves. The dual ignition provided by these two spark plugs causes an efficient combustion since both spark plugs are in a comparatively small chamber communicating with the piston 35 chamber, each of these chambers or ports in which the plugs are located being full of fresh fuel at the time the explosion occurs.

The two sleeves of the valve are each provided 40 with openings which are adapted to be moved into registration at the proper period, and one of the sleeves is open to receive the other sleeve within the same. The inner sleeve is provided with a pair of openings on each side of the plane of symmetry of the cylinder and the inner sleeve between these two openings is partitioned or closed by a central drum having flaring guide surfaces which direct the fuel and burnt gases forward 45 and away from the openings in the sleeve. The incoming fuel is supplied thru one end of these two valve sleeves to the cylinder when the one opening in the inner sleeve is properly positioned adjacent to the opening 50 in the housing chamber and after the inner

sleeve has been moved, the second opening is moved into registration with the chamber opening to permit the exhaust of the burnt gases thru the other end of the two sleeves. The sleeves will therefore be cooled by the incoming fuel so as to prevent the excess temperatures which might otherwise result from the hot burnt gases. The sleeves are heated and cooled in such rapid succession that they assume a practically permanent size, and undue expansion is therefore eliminated.

A further object of the invention is the provision of cams which operate the valve sleeves, these cams being designed so that the sleeves are rapidly moved when they are in motion and so that they remain stationary for a comparatively long time during the pressure periods of the engine. A pair of cams is provided for the operation of a reciprocating sleeve operating member for the outer sleeve and a similar pair of cams and cam operating slide member is provided for the operation of the inner sleeve. Each of the sleeves has an upwardly projecting lug by which they are operating from the cam operating slide. The cams are contained in a chamber or housing so that the proper oiling of the cams and sleeves may be provided for. The lubrication is preferably of the forced or positive nature and the oil is directed thru the hollow cam shafts and oils the cam shaft bearings, the cam surfaces and the cam striking blocks provided in the cam slides. A constant level of the oil is maintained in the reservoir or housing, the excess being carried away to a sump by means of return pipes. The valve sleeves themselves are lubricated from the reservoir by means of oil which passes thru holes in the outer sleeve so that it may find its way between the two sleeves.

Further objects and advantages of the invention will be more fully set forth in the following description, in the accompanying claims, and in the drawings wherein one embodiment of the invention is set forth for purposes of illustration. Referring more particularly to the drawings:

Fig. 1 is a vertical section taken thru the plane of symmetry of the valve or cylinder

showing the dividing wall of the inner sleeve in full lines.

Fig. 2 is a transverse vertical section on the line 2—2 of Fig. 3.

5 Fig. 3 is a plan view showing the top of the oil housing in section.

Fig. 4 is a detail view of the outer sleeve.

Fig. 5 is a detail view of the inner sleeve.

10 Fig. 6 is a horizontal section taken thru the inner sleeve.

15 Figs. 7, 8, 9 and 10 are diagrammatic representations showing the various stages of the operation of the engine, Fig. 7 showing the piston starting to rise to force the burnt gases out of the left side of the valve sleeves; Fig. 8 representing the end of the intake period; Fig. 9 representing the start of the compression period and Fig. 10 showing the engine immediately preceding the ignition period.

20 Referring more particularly to the drawings by reference numerals, the invention is represented as applied to a four cycle internal combustion engine and for the purpose of illustration a single cylinder having the customary piston connected in a customary crankshaft, not shown, is illustrated. Obviously the invention is intended to be used with multiple cylinder engines.

30 The piston 1 is shown as operating in a cylinder 2, above which is the stationary sleeve containing chamber designated generally 4. In the case indicated the engine is shown as adapted to be cooled by a water circulating medium and for this purpose a water jacket 3 is provided around the cylinder and around the combined intake and exhaust ports 5.

40 Mounted within the sleeve chamber 4 are two sleeves, an outer sleeve 6 and an inner sleeve 7; the inner sleeve being slidably mounted within the outer sleeve. The outer sleeve is unobstructed thruout its length and is provided with an opening 8 on each side 45 of the sleeve. The inner sleeve is provided with a pair of openings 9 one on each side of the sleeve and a pair of openings 10 also located one on each side of the sleeve. The openings 9 and 10 are adapted to be moved in registration alternately with a port aperture 11 provided in the outer sleeve chamber, and when the openings 8 in the outer sleeve 6 are in registration with the opening 11 and also 9 or 10 the 55 fuel or the burnt gases may travel into or out of the cylinder. The inner sleeve 7 is divided centrally by a partition drum 12 which is rigidly connected to the cylindrical sleeve wall and which is provided with a flaring deflector 13 to deflect the inwardly flowing fuel into the openings 10, a similar deflector 14 being provided on the opposite side of the partition wall 12 to deflect the burnt gases as they travel into the inner sleeve and straighten these gases out and direct them 60 65

toward the left end of the sleeve where they may be exhausted into a muffler or into the atmosphere in the customary manner. The attaching nut 15 serves to mount the curved deflector in place and attaches the deflector 13 and the deflector 14 to the partition wall 12.

70 Each of the sleeves 6 and 7 has an upwardly extending lug designated 16 and 17 respectively. The lug 17 extends upwardly thru a slot 18 provided at the right end of the outer sleeve 6 so that it may be moved along and guided by the slot 18. These two lugs are operated by two cam slides and for this purpose each lug is provided with a pin 75 or stud 19 and 20, upper fittings of which are mounted in the cam slides. The stud 19 on the outer sleeve is mounted in a hole at the left end of the cam slide 21 and the stud 20 on the inner sleeve is mounted at the 80 right side of the cam slide 22. The two cam sleeves 21 and 22 have inwardly projecting portions 23 and 24 respectively in which the studs 19 and 20 are fitted with a clearance fit so that the cam slides may be moved vertically when disassembling and thus be freed from engagement with pins 19 and 20.

85 The cam slide 21 for the outer sleeve has an upwardly extending projection 25 which rigidly supports a cam striker block 26. A 90 bolt 27 serves to connect the block 26 to the support 25. The cam slide 22 which operates the inner sleeve is likewise provided with a cam striker block 28. The two blocks 26 and 28 are oppositely reciprocating back and forth by means of cams mounted upon the two camshafts 29 and 30. These camshafts support the outer slide cams 31 and 32 and support the two cams 33 and 34 which operate the cam striker block 28 for the operation 95 of the inner sleeve. The cam striker block is shown as having a substantial triangular shape and the cams are so designed that engagement is maintained with both of the cams of the striker block at all times. The cams operate to move the striker block positively back and forth which thus operates the cam slide mounted upon balls 35 and thus causes the operation of the sleeve to which it is connected.

100 The cam slides are retained in place by the upper portion 36 of the cam housing 37 and a top inclosure 38 is provided to entirely house the cams and provide an oil chamber or reservoir adapted to be maintained partly 105 filled with oil by a suitable force feed oil supply.

110 The camshafts 29 and 30 are each provided with gears 39 which intermesh together, one of which being rigidly connected to a bevel gear 40 which is operated by a pinion 41 mounted at the upper end of a camshaft 42 which is operated in the customary manner from the engine. The camshafts are thus constantly rotated, at the 115

proper speed and this causes the constant rotation of the cams to reciprocate the sleeves back and forth.

The camshafts and cam slide plugs are mounted directly above the cylinder of the engine and as will be seen from Fig. 2 the two valve sleeves 6 and 7 and the stationary supporting sleeve of chamber 4 are located only a slight distance above the limit of travel of the piston. The water jacket 5 extends up and around the combined intake and exhaust ports 43 and 44 and these exhaust ports are of comparatively large size where they communicate at their lower ends as at 45 with the upper end of the cylinder. The valve ports extend upwardly so that they may communicate with practically the entire vertical extent of the valve sleeve openings when these openings are in the proper position. The fuel flows into the two valve ports 43 and 44 simultaneously thru the openings provided on the opposite sides of the sleeves and similar flows out of the two ports simultaneously when the sleeves are in the proper position for the exhaust period.

Referring more particularly to Figs. 7 to 10 inclusive, the cams 31 and 32 controlling the cam striker block 26 are indicated in full lines in these figures and likewise the opening 8 in the outer sleeve 6 is indicated in full lines. The cams 33 and 34 which control the cam striker block 28 are shown in dotted lines and the openings 9 and 10 of the inner sleeve 7 are correspondingly shown in dotted lines in a diagrammatic manner. As shown in Fig. 7, the cams and the striker blocks are in such position that the opening 8 is in registration with the opening 9 and both of these openings are located centrally above the cylinder and therefore in registration with the opening port 11 as also shown in Fig. 6. In this position the piston is just starting to rise so as to exhaust the burnt gases which will be deflected to the left by the deflector 14 shown in Fig. 6. The cams 31 and 32 rotate in the direction indicated by the arrows and these cams are provided with surfaces such as 46 which are concentric with the centers of rotation. Similar concentric surfaces 47 are also provided on the cams so that when the cam striker block is located by a surface 46 of one cam it will be in contact with a surface 47 of the other cam, and as these surfaces are concentric with the axis of rotation no movement of the striker block will obtain.

The striker block, due to the design of the cams, is maintained stationary for a considerable period of time which is about to start with the engine at the period indicated in Fig. 7, during which time the piston travels upwardly and exhausts the burnt gases while the two valve slides are stationary. After a slight movement of the piston

from the position indicated in Fig. 7 the block 26 remains stationary and consequently the outer sleeve 6 is stationary but the cam surfaces of the cams 33 and 34 are such that the block 28 will be moved to the left 70 in a positive manner so as to close the cylinder ports and shortly thereafter place the openings 8 and ports 11 in registration with the intake openings 10 of the inner sleeve. The piston will then travel downwardly 75 until it reaches a point indicated in Fig. 8 during which time the sleeves remain stationary while the fuel is sucked into the cylinder.

The compression period starts, as indicated, in Fig. 9 with the port 8 removed to the left of the center of the cylinder and consequently out of registration with the ports 11. Thus the outer sleeve 6 is placed between the ports 11 and openings 9 and the two sleeves remain in this position during the compression period and consequently no relative movement takes place while the sleeves are subjected to a pressure at the ports 11. It is therefore unnecessary to provide piston rings on the sleeves since considerable distance extends between the openings 8 and 9 during pressure periods and thus prevents any leakage from taking place around and between the sleeves. After the compression period has been completed, as indicated in Fig. 10, the explosion takes place by the firing of the spark plug 48 in each of the cylinder ports.

During the interval occurring between the positions indicated in Figs. 9 and 10, the sleeves and the cam striker blocks are maintained stationary and these parts are still maintained stationary for some time after the ignition period and during the start of 100 the expansion stroke of the piston. The cams which control the two striker blocks, as shown, are so designed that the motion imparted to the blocks is very quick so that a very rapid opening and closing of the valves 105 will be produced. The valve openings 8, 9, 10 and 11 being wide and extending thruout nearly the entire circumference of the sleeves will produce and make possible a large valve opening to permit the rapid flow of 110 fuel and exhaust gases. The valve being operated positively in both directions permits their rapid opening and closing since the time delay of a spring at high speeds is not present.

The entire head of the engine may be detachable so that the entire valve mechanism may be removed by the removal of the bolts 49. The upper housing 38 and the upper part 36 of the valve 125 housing are adapted to be easily detached for inspection and removal of the cam slides. In order to prevent the incoming fuel mixture from finding its way between the valve sleeves 6 and 7, an auxiliary sleeve part 50 is fixed in 130

position to the intake pipe 51 and extends some distance within the inner sleeve 7.

We are aware that various changes and modifications may be made in our invention without departing from the spirit or scope thereof and we do not intend to be limited to the precise form of construction which has been chosen herein for the purpose of our invention.

10 We claim:

1. In an engine of the class described, a cylinder, a valve port at one end of said cylinder, a piston adapted to reciprocate in said cylinder, a pair of sleeves mounted one within the other adjacent to said valve port, a pair of openings in the inner sleeve adapted to communicate successively with said valve port, a partition within said inner sleeve to close said sleeve between said pair of openings, an opening in the outer sleeve adapted to register periodically with said valve port, means for reciprocating each of said sleeves longitudinally, and means fixed to said inner sleeve for guiding said outer sleeve.

25 2: In an engine of the class described, a cylinder, a pair of valve ports at the outer end of said cylinder, a piston adapted to reciprocate in said cylinder, a pair of sleeves mounted one within the other adjacent to said valve ports, a pair of oppositely positioned intake openings in the inner sleeve and a pair of oppositely positioned exhaust openings in the inner sleeve adapted to communicate successively with the said valve ports, a partition within said inner sleeve to close the same between the inlet and the exhaust openings, a pair of openings in the outer sleeve adapted to register periodically with said valve ports, a pair of engine driven rotatable cams for each sleeve, and a reciprocating member operated by each pair of said cams and connected to the sleeves to positively reciprocate the same in both directions.

30 3: In an internal combustion engine, a cylinder, a pair of valve ports extending upwardly and opening into the head of said cylinder, a pair of telescoping reciprocating sleeves the outer of which is provided with a pair of openings, the inner of which is provided with two pairs of openings, a partition in said inner sleeve located between the pairs of openings, and means for reciprocating said outer and inner sleeve to move the openings so that they will register simultaneously with both ports of the cylinder, as and for the purpose described.

35 4: In an internal combustion engine, a cylinder, a pair of valve ports extending upwardly and opening into the head of said cylinder, a pair of telescoping reciprocating sleeves the outer of which is provided with a pair of openings, the inner of which is provided with two pairs of openings, a partition in said inner sleeve located between the pairs of openings, means for reciprocating said out-

er and inner sleeve to move the openings so that they will register simultaneously with both ports of the cylinder, said sleeves being located immediately adjacent to the piston of the engine when the piston is at its top dead center, and said sleeves being arranged to extend transversely at the top of the cylinder, as and for the purpose described.

5 5: In an internal combustion engine, a cylinder, a pair of valve ports extending upwardly and opening into the head of said cylinder, a pair of telescoping reciprocating sleeves the outer of which is provided with a pair of openings, the inner of which is provided with two pairs of openings, a partition in said inner sleeve located between the pairs of openings, means for reciprocating said outer and inner sleeve to move the openings so that they will register simultaneously with both ports of the cylinder and also maintain said sleeves stationary during the entire period of any pressure period of the engine.

In testimony whereof we affix our signatures:

BRIAN DE KRUYFF VAN DORSSSEN.
